UNITED STATES PATENT OFFICE.

ISAAC CHORLTON AND GEORGE L. SCOTT, OF MANCHESTER, COUNTY
OF LANCASTER, ENGLAND.

BED-FRAME AND BEDSTEAD.

SPECIFICATION forming part of Letters Patent No. 402,903, dated May 7, 1889.

Application filed October 24, 1888. Serial No. 288,995. (No model.) Patented in England January 1, 1887, No. 21.

To all whom it may concern:

Be it known that we, ISAAC CHORLTON and GEORGE LAMB SCOTT, subjects of the Queen of Great Britain and Ireland, residing at 5 Manchester, county of Lancaster, England, have invented certain Improvements in the Construction of Bed-Frames and Bedsteads, (for which we obtained a patent in Great Britain, No. 21, dated January 1, 1887,) of which the following is a specification.

Our said invention relates chiefly to the construction of iron bed-frames and bedsteads, and has for its object to dispense with the usual dovetail attachments employed to 15 connect together the members of the bedstead at the four corners, as is well understood. Owing to the difficulty of obtaining a perfect fit, the said dovetails are seldom sufficiently secure to prevent relative movements of the parts and to keep the ends of 20 the bedstead exactly at right angles horizontally and vertically to the side members, while owing to variations arising in molding and casting, the parts intended to come together 25 and which should be interchangeable are not always so. In addition to these defects, the dovetail is inherently weak, and is frequently broken. According to our invention we dispense with the said dovetails and unite the 30 bedstead at the corners by means of fittings having flat surfaces with interlocking projections and recesses, the parts being held together by bolts or studs.

In order that our said invention may be 35 properly understood, we will now proceed more particularly to describe the same with reference to the annexed sheet of drawings.

Figure 1 is a side view of one corner of a bedstead fitted together in our improved 40 manner. Fig. 2 is a view of the joint from the end of the bed. Fig. 3 is a plan of the upright end pillar of the bedstead with its corner-fitting shown detached from the fitting belonging to the side and end member of the 45 bedstead, which latter is shown at Fig. 4. Fig. 5 is a face view of the corner-fitting shown at Fig. 3. Fig. 6 is a face view of the corner-fitting shown in plan at Fig. 4. Fig.

7 is a perspective view showing detached the bracket provided with the plug.

As clearly indicated by these figures, the corner-piece *a* is cast on or secured to the upright end pillar, *b*. The face of the corner-piece *a* is flat and carries a projection, *a'*, from which a stud, *c*, extends, the said stud having a square neck at *c'*. The stud *c* passes through a slot, *d'*, in the bracket *d*, and the said bracket is also recessed, as clearly shown at Fig. 4, to receive the projection *a'*. (Seen in Fig. 3.) When the bracket *d* and corner-piece *a* are placed together and secured by a nut, *e*, on the stud *c*, the flat faces thus held in contact prevent the bedstead from being twisted and secure absolute perpendicularity of the end pillar, *b*. The square neck of the 65 stud *c*, fitting the slot *d'*, is an additional security for preventing movement of the parts. In the example illustrated only one fitting-face on the corner-piece *a* is required, as the bracket *d* carries not only the tubular side 70 member, *f*, but also the angle-iron end member, *g*. To receive the side member, *f*, the bracket *d* is cast with a plug, which enters the tubular side member, *f*, and is secured thereto by a bolt, *h*, or other means. The 75 bracket *d* is formed to receive the angle-iron end member, *g*, to which the elastic mattress *i* is attached. When the mattress is strained and secured to the end members in position, nothing remains but to bolt the brackets *d* to 80 the corner-pieces *a*, and the bedstead carrying its mattress is complete, thus forming a simply-connected and strong bedstead, which is not liable to the weaknesses and distortions of similar bedsteads connected together 85 by dovetail fittings.

We prefer, in the manufacture of our invention, to make the improved joint of constant proportions, so that the parts may be interchangeable, not only for the same size 90 and class of bedstead, but also for bedsteads of different types of construction.

What we claim is—

In iron bedsteads, the brackets *d*, carrying the tubular side members, *f*, and angle-iron 95 ends *g*, said brackets *d* being formed with a

recess, in combination with the corner-brackets a , formed with a projection, a' , which fits the recess in the brackets d , and a screwed stud, c , passing through the bracket d , and secured by a nut, e , substantially as described and shown.

In testimony whereof we have signed our

names to this specification in the presence of two subscribing witnesses.

ISAAC CHORLTON.
GEORGE L. SCOTT.
